A. Randolph Jr.
Attorney

UNITED STATES PATENT OFFICE.

HARM L. BASHAM, OF WOODBURY, TENNESSEE.

AUTOMATIC SPARK CONTROL.

Application filed January 10, 1928. Serial No. 245,803.

This invention relates to a spark control for internal combustion engines, and has for one of its objects to provide a novel, simple and inexpensive device of this character which shall be especially adapted for use in connection with the timer of an internal combustion engine of that type known as the Ford, which shall be adapted to be operated by the fan of the engine in a manner to advance the position of the shell of the timer in exact relation to the speed of the engine, and which shall be adapted to be supported from the steering column of the automobile equipped with the engine and readily connected to the fan and to the timer shell.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view partly in elevation and partly in vertical section of an internal combustion engine equipped with a spark control embodying my invention, and

Figure 2 is a top plan view of the engine and spark control.

Referring in detail to the drawing, 1 designates the cylinder block, 2 the timer, and 3 the fan of an internal combustion engine of the type known as the Ford. The timer 2 comprises a shell 4 which is mounted to permit it to be turned in one direction to advance of the spark and in the opposite direction to retard the spark. The fan 3 embodies a hub 5, blades 6 and a pulley 7, and it is mounted upon a shaft 8 which is supported from the cylinder block 1 by a socket 9.

The spark control comprises a lever 10 which is pivotally mounted between its ends, as at 11, upon a bracket 12 which is secured, as at 13, to and extends upwardly from the steering column of the automobile equipped with the engine. The lever 10 is provided at opposite sides of its pivot 11 with openings 15 and 16 which extend longitudinally thereof. One end of the lever 10 is connected to the arm 17 of the timer shell 4 by a link 18, and the other end of the lever is connected to the arm 19 of an elbow lever 20 by a link 21. The link 18 passes through one of the openings 15, and the link 21 passes through one of the openings 16, the open-

ings permitting the links to be connected to the lever at different distances from its pivot 11.

The levers 10 and 19 are horizontally arranged, and the lever 20 is pivoted, as at 22, upon the rear end of a horizontal arm 23 secured to and extending rearwardly from the vertical arm of the bracket 9. The arm 23 may be bolted or welded or secured in any other suitable manner to the bracket 9. The other arm 24 of the lever 20 is provided at its free end with an upstanding lug 25 which is positioned at the rear end of the shaft 8 and is provided in its front side with a concave recess 26 axially aligned with the shaft.

The shaft 8 is hollow, and slidably and rotatably mounted therein is a rod 27 which has its rear end positioned in the recess 26 of the lever lug 25 and is provided at its front end with a head 28 having a rounded front side. A plate 29 is secured, as at 30, to the front side of the fan hub 5, and it is provided with forwardly directed and angularly related arms 31 and with an opening 32 for the passage of the rod 27. Elbow levers 33 are pivoted as at 34 to the arms 31, and present inwardly directed arms 35 and rearwardly directed arms 36. The arms 35 contact at their free ends with the head 28, and the arms 36 are provided at their free ends with weights 37. A coil spring 38 which is secured to the pivot 11 and to the lever arm 19, constantly urges the weights 37 inwardly or in the direction of each other.

When the engine is at rest, the spring 38 holds the timer shell 4 in its fully retarded position, and it also holds the weights 37 in their innermost positions. The spring 38 will hold the timer shell 4 and the weights 37 in these positions while the engine is operating at minimum speed. As the speed of the engine increases, the weights 37 move outwardly, and the resulting rearward movement of the lever arms 35 will move the rod 27 rearwardly. The rod 27 will rock the lever 20 in a direction to carry the free end of its arm 24 rearwardly and the free end of its arm 19 forwardly. This movement of the lever 20 will move the link 21 forwardly and the link 18 laterally, with the result that the timer shell 4 will be rotated in a direction to advance the spark. The advancement of the spark will be in direct relation to the increase in the speed of the engine. As the

speed of the engine reduces, the spring 28 will move the parts in the reverse direction, with the result that the spark will be retarded.

It should be understood that the drawing 5 is merely illustrative and does not pretend to give exact proportions. Furthermore, the said drawing is illustrative of a preferred construction, it being my expectation that various changes and modifications may be 10 made without departing from the spirit and scope of my invention.

What is claimed is:—

1. A spark control for the timer of an internal combustion engine, comprising a hollow rotatable member driven from the engine, 15 a lever pivotally supported between its ends, a link connecting one end of the lever to the shell of the timer, an elbow lever pivotally supported adjacent one end of the member, 20 a link connecting the other end of said first lever to one end of the elbow lever, a spring urging the elbow lever in one direction, a rod slidably carried by the rotatable member and bearing against the other end of the elbow lever, and weighted levers pivotally connected to the rotatable member and contacting with the rod. 25

2. A spark control for the timer of an internal combustion engine, comprising a 30 bracket fixed to the engine, a hollow shaft fixed to the bracket, a member rotatably mounted on the shaft, a horizontal arm secured to the bracket, a vertical arm supported adjacent the engine, a horizontal lever

pivoted between its ends to the vertical arm, 35 a link adjustably connected to one end of the lever and connected to the shell of the timer, an elbow lever occupying a horizontal position and pivoted to the horizontal arm and having one of its ends provided with an up-standing lug located adjacent an end of the shaft, a link adjustably connected to the other end of said first lever and to the other end of the elbow lever, a rod slidably mounted in the shaft and contacting at one end with the 40 lug, weighted levers pivotally connected to the member and contacting with the other end of the rod, and a spring connected to the elbow lever and to the vertical arm. 45

3. A spark control for the timer of an 50 internal combustion engine, comprising a hollow shaft supported on the engine, a member rotatably mounted on the shaft and driven from the engine, a rod slidably carried by the shaft, weighted levers pivoted to the rotatable member and contacting with an end of the rod, an elbow lever pivotally supported from the engine and provided at one end with a lug contacting with the other end of the rod, a lever pivotally mounted between its 55 ends, a link connecting one end of the elbow lever and one end of said last lever, a link connecting the other end of said last lever and the shell of the timer, and a spring urging the elbow lever in one direction. 60

In testimony whereof I affix my signature.

HARM L. BASHAM.
